Attorney.

UNITED STATES PATENT OFFICE.

FRANCIS A. NOLAN, OF ST. PAUL, MINNESOTA.

RESILIENT SHOE-HEEL.

1,292,360.

Specification of Letters Patent. Patented Jan. 21, 1919.

Application filed October 21, 1916. Serial No. 126,903.

To all whom it may concern:

Be it known that I, FRANCIS A. NOLAN, a citizen of the United States, residing at St. Paul, in the county of Ramsey and State of Minnesota, have invented a new and useful Improvement in Resilient Shoe-Heels, of which the following is a specification.

This invention relates to certain new and useful improvements in resilient shoe heels designed for permanent attachment to a shoe whereby a tight joint is effected so as to avoid the collection of dirt, moisture, and the like, between the adjacent portions of the heel and shoe, and has for an object to provide a heel of this type which is so formed that when the same is positioned upon the shoe, it is securely retained not only by means of the tacks, nails, or like devices employed, but also through the medium of a suction-sealing action between the said shoe and heel.

In certain respects this application may be regarded as a divisional application from that filed in the United States Patent Office by me July 17, 1916, Serial Number 109,654, and from which it differs principally through the fact, that, after having been secured in place, it affords an absolutely flat-tread surface which is to be desired.

Other and further objects and advantages of the invention will be hereinafter set forth and the novel features thereof defined by the appended claims.

In the drawings:

Figure 1 is an inverted plan of my improved lift;

Fig. 2 is a section taken on the line X—X of Fig. 1 showing one form of nail receiving and retaining device employed;

Fig. 3 is a section of a modified form of lift taken, for example, on the line Y—Y of Fig. 1;

Fig. 4 is a section similar to that of Fig. 2, showing another form of nail receiving and retaining device;

Fig. 5 is an inverted plan of a modified form of the invention;

Fig. 6 is a section taken on the line Z—Z of Fig. 5;

Fig. 7 is a side elevation of a detail of a shoe showing the invention applied thereto; and

Fig. 8 is a side elevation of a detail of a shoe, partly in section, and showing the invention partly in section and broken away to illustrate the manner in which the con-

tinuous contacting upper free edge of the lift engages the shoe heel.

Like numerals of reference refer to like parts in the several figures of the drawing. 60

Referring to the drawing, the reference character A represents the improved cushioning device which is adapted for attachment to the usual heel 5 of a shoe, boot, or like form of foot apparel, indicated by the 65 character B.

It is well-known that cushion lifts are at present on the market which are provided with concave upper and convex lower surfaces and that the purpose of such construction or formation is to increase the permanent attachment of the lift to the heel of the shoe. These devices, however, have proven to be deficient in a number of ways and it is to overcome such defects that the present 75 invention has been devised.

In the drawings, the resilient lift or heel A is provided with a central flat face portion 6 of any yieldable material, such as rubber, of suitable thickness and molded into a shape 80 generally conforming to that of the ordinary shoe heel, but on a reduced scale; while extending entirely around the edges of the portion 6 and angularly inclined therefrom is a flange 7 in the nature of a bevel of a 85 thickness equal, or substantially so, to that of the base, the continuous free edge 8 of the flange or bevel lying in a single plane so that when the upper surface 9 of the lift formed as described is positioned upon the 90 heel of the shoe, an absolutely air-tight joint entirely around the lift results with the shoe heel, no cement whatsoever being required to attain this end. Consequently, when the fastening means, as nails, are driven through the base portion of the lift and into the heel of the shoe, the flat base portion 6 of the lift is forced into engagement with the heel and the edge 8 of the lift thus held firmly in place, the increased suction produced by 100 thus forming the device greatly enhancing its security upon the heel and precluding the possibility of entrance of dirt and moisture. If desired the bevel may be formed of increasing thickness from its jointure with the base portion to the free edge of the bevel, so that when the base portion is tacked to the shoe heel, there is less possibility of a rounding edge resulting due to increased pressure on the outer edge. 105

In Fig. 6 is shown a lift of a modified construction in that the body portion is

10 molded with an uninterrupted dished surface 10, the continuous free edge 11 of which lies in a single plane as in the preferred form whereby when the lift is subjected to 15 pressure, the surface 10 is flattened out and a perfect vacuum created throughout the entire upper surface of the lift, thus materially increasing the resulting suction and the permanent securance of the lift to the heel of the shoe. As illustrated in this figure, the contour of the convex lower surface and that of the concave upper surface of the lift may be such as to effect a cushioning medium, the depth of which increases from 20 a central point of the device as it approaches the outer continuous edge thereof so that when tacked to the shoe heel, the greatest density occurs about the outline of the heel where the greatest wear is generally required. Such construction also obviates the possibility of a rounding edge mentioned heretofore.

In order to secure the lift in place upon the lower surface of the heel of the shoe, washers such as 11' (see Figs. 2, 3 and 6) or a continuous penetrable plate 12 (see Fig. 4) are or is embedded in the lift approximately centrally and equidistant from the marginal edge thereof, through which 25 small nails (not shown) may be driven into the shoe heel, it being understood that the heads of the nails are engaged by the plate 12 or within the washers 11, as the case may be. A fuller description of the particular 30 nail retaining washers and plate employed may be had by reference to my co-pending application entitled "Rubber heels", filed in the United States Patent Office July 17, 1916, and bearing Serial Number 109,654.

40 By molding the lift with a concave upper and a convex lower surface and of substantially uniform depth throughout, it will be seen that when the lift is placed upon the under side of the shoe heel and the securing 45 means employed, the lift is forced into flattened position so as to form a cushioning medium of finished appearance presenting a smooth lower tread surface.

With reference to the preferred form, it 50 may be added that the provision of a central flat base portion, through which the securing means are driven, enables the entire upper surface of the lift to be forced and retained in closer juxtaposition with respect 55 to the shoe heel than is the case in connection with the known art and, in fact, with the modification shown in this application wherein the upper surface of the lift is of a continuous curvature. In the preferred 60 form, it is only necessary to apply the securing means through the flat base portion which, as will be appreciated, holds the bevel portion firmly in place against the heel. The plate or washers employed are also embedded 65 within the base portion and in this way the

life of the heel is materially increased so that maximum wear of the lift is accomplished without exposing the securing means.

Another prevalent disadvantage with lifts in common use and which are provided with 70 dished or concave upper sides is that the outer edge is not molded with any or sufficient angularity with regards the dished side, and as a result when the lift is secured upon the heel, the outer edge is caused to 75 assume a downward and inward inclination which necessitates trimming to finish the appearance of the attached lift. It is well known that the English type of shoe now 80 widely used features a heel, the edge of 85 which generally lies in a vertical or an outwardly inclined plane and in this way differs from the military shoe used. It is applicant's intention to so form his improved lift whereby, when attached to the particular 85 shoe being equipped, the corresponding edges of the heel and lift, when such two portions are secured together, will be in one continuous plane and thus avoid any further finishing work. In the several figures of the drawing, the lift is shown with an outer extremity or edge 13 which, while the lift is unattached, is inclined outwardly from the plane in which the marginal edge 8 or 11 of the lift lies. Consequently, when the lift is affixed to 90 the heel, the edge 13 thereof is caused to assume a different angularity with respect to the plane of the marginal edge. It is to be understood that this invention contemplates 95 molding the heels so that the edges thereof 100 will assume various angularities in the light of the above disclosures whereby shoes of the several different types may be properly equipped.

In accordance with the patent statutes, I 105 have described the principles of operation of my invention, together with the apparatus which I now consider to represent the best embodiment thereof, but I desire to have it understood that the construction shown is 110 only illustrative, and that the invention can be carried out by other means and applied to uses other than those above set forth within the scope of the following claims.

Having described my invention, what I 115 claim as new and desire to protect by Letters Patent is:

1. A heel construction, comprising, an elastic body having a flat central tread portion, an integral bevel portion projecting from and extending entirely around said base portion in a series of changing angles with respect thereto, and means for fastening said body upon the heel of a shoe.

2. A heel construction comprising an elastic body having a flat central base portion, an integral bevel portion projecting from and extending entirely around said base portion, the angularity of said bevel with respect to the plane of said base gradually changing 120 125 130

from the front to the rear thereof, and means for fastening said body upon the heel of a shoe.

3. A heel construction comprising an elastic body having a flat central base portion provided with a heel engaging side and a tread surface, said side and surface lying in parallel planes, an integral bevel portion of gradually increasing thickness projecting from and extending entirely around said base portion in a series of gradually changing angles with respect thereto, the marginal edge of the heel engaging side lying in a single plane, and means for fastening said body upon the heel of a shoe.

4. A heel construction comprising an elastic body having a flat central base por-

tion, an integral bevel portion projecting from and extending entirely around said base portion in a series of gradually changing angles with respect thereto, the marginal edge of said bevel lying in a single plane removed from that of said base portion, and means for fastening said body upon the heel of a shoe.

5. A heel construction, comprising, an elastic body formed with a raised tread surface, a dished base surface and an integral marginal bevel portion extending entirely around said heel in a series of gradually changing angles.

In testimony whereof, I have signed my name to this specification.

FRANCIS A. NOLAN.
